UNITED STATES PATENT OFFICE.

THOMAS P. CHISHOLM, OF SAGINAW, MICHIGAN, ASSIGNOR TO A. T. FERRELL & CO., OF SAGINAW, MICHIGAN, A CORPORATION OF MICHIGAN.

BELT FOR SPEED-VARYING DEVICES.

1,238,494.

Specification of Letters Patent. Patented Aug. 28, 1917.

Application filed May 12, 1916. Serial No. 97,017.

To all whom it may concern:

Be it known that I, THOMAS P. CHISHOLM, a citizen of the United States, residing at Saginaw, in the county of Saginaw and 5 State of Michigan, have invented certain new and useful Improvements in Belts for Speed-Varying Devices; and I do hereby declare the following to be a full, clear, and exact description of the invention, such as 10 will enable others skilled in the art to which it appertains to make and use the same.

This invention is a power transmission belt adapted for use in speed-varying mechanisms of the type employing two pairs of 15 cone-shaped disks, the disks of each pair slidably mounted on a shaft and adapted to be moved toward and from each other. Such speed-varying mechanisms are usually also provided with means whereby the disks 20 of one pair may be moved toward or from each other while simultaneously the other pair of disks are moved away from or toward each other.

The belts used are known as V-belts and 25 usually consist in a flat band or its equivalent, to which blocks of wood or like material are secured, the blocks located crosswise the belt and having their ends beveled to suit the faces of the conical disks. The ends 30 of the blocks are usually tipped with leather, which provides the driving surface.

It is the object of my present invention to provide a belt for this class of speed-varying machines that will be simple in 35 construction, light, yet strong and durable; easily assembled and capable of exerting a great degree of tractive effort.

A further object is to so construct the belt that its flat central body (this being the 40 part of the belt that transmits the pull of the load from one pair of cones to the other) may be formed integral with the traction tips that bear against the working faces of the disk, for purposes that will appear later 45 in the specification.

With these and certain other objects in view which will appear later in the specification, my invention comprises the device described and claimed, and the equivalents 50 thereof.

In the drawings, Figure 1 is a plan view of a short length of my improved belt, flat-

tened, the traction tips being extended to show the manner in which they are formed.

Fig. 2 is a similar view showing the tips 55 bent into their working position.

Fig. 3 is an enlarged cross section on line 3—3 of Fig. 2.

Figs. 4 and 5 are diagrammatic views showing the relation of the V-belt to the two 60 sets of conical disks on which it runs. Fig. 6 is an enlarged side view of a part of the belt as it appears when bent.

As is clearly shown in the drawing, the V-belt consists in a single band or belt of 65 leather or equivalent material, the band being cut to form a central strap or tension body 1, having a plurality of laterally projecting wings or tips 2.

These tips are preferably formed by making transverse slits 3 in the edges of the band, at suitable intervals, and providing an opening 4, which may be made by punching or otherwise, at the inner end of each slit. The opening 4 may be of any suitable shape, but I prefer to make it substantially elliptical, or elongated, with curved ends, as indicated in Fig. 1. There is thus formed along the edges of the band 1 a plurality of tips 2, which, when bent nearly 75 at right angles to the body, as shown in Fig. 3, form traction members that tightly grip the working faces of the usual cone disks 5 and 6.

Spacing blocks 7 of wood or equivalent 85 material are secured to the body 1 between each pair of traction members or tips 2. The blocks may be secured to the body of the belt in any suitable manner, as by screws 8, and the tips may if desired be secured 90 to the ends of the blocks by nails 9, or otherwise, although for many classes of service it may not be necessary to fasten the tips 2 to the ends of the blocks.

It will be noted that in my improved 95 V-belt the body 1 of the belt transmits the pull of the load from one set of disks, as the driving set 5, Figs. 4 and 5, to the driven set, 6, and that this load is transmitted by reason of the tension in the fibers of the 100 body 1, as in ordinary flat belt transmissions. But it will also be noted that the driving traction is transmitted to the body of the belt through the tips 2, which are

gripped by the working faces of the disks. The entire traction is not transmitted from the tips to the body of the belt through the blocks 7 and their fastenings 9 and 8, as is the case where the tips are made separate from the belt and merely attached to the ends of the block, but, on the contrary, a considerable part of the tractive force is transmitted direct from the tips 2 to the body 1 by reason of the fact that the tips themselves are integral with the body of the belt. Thus the fastenings 8 are relieved of a large part of the work of power transmission, and the blocks 7 are relieved of a large part of the transverse or splitting stress that would otherwise be brought upon them, and, as above noted, the fastenings 9 may in certain classes of service be entirely dispensed with.

Relieving the blocks 7 and their fastenings 8 of a strain in the manner described results in longer life of the V-belt, for there is less tendency to pull the heads of fastenings 8 through the belt, or to loosen their anchorage in the blocks 7. The blocks are less liable to split under heavy load, and are better able to perform their main function of resisting the compressive stress which is brought upon them by the traction disks.

The V-belt, as indicated in Fig. 6, is almost as free to bend and as flexible as if there were no tips upon its edges.

Having thus described my invention, what

I claim and desire to secure by Letters Patent is:

1. A belt for speed-varying machines comprising a tension band or body, and transverse blocks carried by said band, said tension body being formed with a plurality of laterally projecting tips integral therewith, said tips bent to overlap the ends of said blocks.

2. A belt for speed-varying machines comprising a tension band or body, and transverse blocks carried by said band, said band having a plurality of lateral slits formed along its opposite edges, whereby a plurality of laterally extending tips are formed integral with said body, said tips bent to overlap the ends of said blocks.

3. A belt for speed-varying machines comprising a tension band or body, and transverse blocks carried by said band, said band having a plurality of lateral slits formed along its opposite edges, said band at the inner extremity of each slit formed with an opening, whereby a plurality of laterally extending tips are formed integral with said body, said tips bent to overlap the ends of said blocks.

In testimony whereof I affix my signature in presence of two witnesses.

THOMAS P. CHISHOLM.
